UNITED STATES PATENT OFFICE.

ISADORE LEVIN, OF CHICAGO, ILLINOIS.

REGISTERING DEVICE FOR PRINTING-PRESSES.

1,241,527.

Specification of Letters Patent.

Patented Oct. 2, 1917.

Application filed December 16, 1916. Serial No. 137,362.

To all whom it may concern:

Be it known that I, ISADORE LEVIN, a citizen of the United States, residing at Chicago, in the county of Cook and State 5 of Illinois, have invented certain new and useful Improvements in Registering Devices for Printing-Presses, of which the following is a specification.

This invention relates to improvements 10 in registering devices for printing presses; its object is to provide a device for perfectly registering the paper with the plate in polychrome printing in order that each color shall be properly applied and positioned 15 with relation to the other colors. With the foregoing and other objects in view the invention consists in the combination and arrangement of parts to be hereinafter fully described in the following specification, 20 pointed out in the claims and illustrated in the accompanying drawings which form a part of said specification and in which—

Figure 1 is a side elevation of the guide.

Fig. 2 is a plan view of the same.

Fig. 3 is a longitudinal section in side elevation and is taken on line 3—3 of Fig. 2.

Fig. 4 is an end view of Fig. 1 and is taken on line 4—4 of that figure.

Fig. 5 is a sectional view taken on line 20 5—5 of Fig. 1.

Fig. 6 is a sectional view taken on line 6—6 of Fig. 1.

Fig. 7 is a plan view of the guide strap.

Fig. 8 is a side elevation of the same.

Fig. 9 is a cross section taken on line 9—9 of Fig. 7.

Fig. 10 is a similar view taken on line 10—10 of Fig. 8.

Fig. 11 is an inverted plan view of the 40 sliding guide and finger employed.

Fig. 12 is a top plan view of the same.

Fig. 13 is a section taken on line 13—13 of Fig. 12.

Fig. 14 is a section taken on line 14—14 of Fig. 12.

Fig. 15 is a plan view of a portion of the guide strap and auxiliary guide strap.

Fig. 16 is a plan view of the telescoping guide carried by the auxiliary strap.

Fig. 17 is a view of the same extended.

Fig. 18 is a plan view of the graduated portion of the telescoping guide.

Fig. 19 is an end view of the Fig. 16 taken on line 19—19.

Fig. 20 is a section taken on line 20—20 of Fig. 18.

Fig. 21 is a section taken on line 21—21 of Fig. 17.

Fig. 22 is a similar view taken on line 22—22 of Fig. 17.

Fig. 23 is a section taken on line 23—23 of Fig. 15.

Fig. 24 is a section taken on line 24—24 of Fig. 25.

Fig. 25 is a view of a portion of a printing press showing the application of my device.

Like reference characters indicate corresponding parts throughout the several views.

The reference numeral 1 designates the bed of the press to the sides of which the frame 2 is secured by screws or in other suitable manner. A filler 2^a being interposed between said frame and press; said frame being slotted longitudinally as at 3 75 to permit the insertion of the tongue 4 of the guide pin block 5 adapted to slide longitudinally of said frame and provided with a plurality of guide pins 6; said tongue 4 being propelled by means of the traveling 80 nut 7 operatively associated with the screw 8 journaled in the ends of the frame 2 and provided with the operating handle or head 9. The pins 6 at one side of the press are adapted for engagement with the apertured 85 portions 10 of the guide strap 11 while the pins 6 at the other side of the press are adapted for engagement with the slotted portion 12 of said strap. The guide strap 90 is formed with lateral shoulders 11^a to retain the sliding guides or registers 13 to be hereinafter described. The said strap 11, further, is provided with the adjusting screw 12^a by means of which the strap may be drawn taut when in position.

Sliding guide 13, 13 of oblong formation are arranged upon said guide strap and each one carries an elongated finger 14 adapted to project over the paper 15 while one edge of said paper is kept true by the 100 abutting straight edge of the guides 13. To move the paper lengthwise of the plate 1 the screws 8 are rotated thus causing the traveling nuts 7 to move the pin blocks together with the guide strap and the guides 105 arranged on said strap. It is obvious that a fine adjustment of the paper with relation to the plate is possible in this manner.

To the guide strap 11 an auxiliary guide strap 16 is secured which lies in a plane at right angles to the plane of said guide strap and upon said auxiliary guide strap a tele-

scoping guide is slidably arranged; said guide comprising the relatively fixed tongue 17 formed with rows of staggered graduations 18, and the relatively movable and adjustable casing 19 slotted longitudinally as at 20, 21 through which slotted portions the adjusting screws 22, 23 extend respectively; the screw 22 serving to retain the tongue 17 and casing 19 in adjusted relation and the screw 23 serving to secure said tongue to the auxiliary guide strap 16. The casing 19 is provided with alined ears 24, 24 through which the finger 25 extends that is adapted to extend beyond the work-engaging edge 15 of the casing 19 and over the adjacent edge of the paper 15 to prevent the same from following the type of the press during the printing operation. The purpose of the telescoping guide is to effect a transverse adjustment of the paper which adjustment is effected by means of the adjusting screw 22 which is used to move the casing 19 with relation to the tongue 17, the said casing engaging and directly moving the paper. The graduations in any staggered row may be consecutively staggered one-thirty-second of an inch, or less if desired, thus affording a very delicate transverse adjustment of the paper by moving the casing 19 along the tongue from one of said graduations to the next in any staggered row.

What is claimed is:—

1. A registering device for printing presses comprising frames secured to each side of the press plate, guide pin blocks slidably carried by said frames, manually operable means for actuating said guide pin blocks, guide pins carried by said guide pin blocks, a guide strap connecting the pins of one pin block with the pins of the other pin block, registers slidably arranged upon said guide strap and fingers carried by said registers.

2. A registering device for printing presses comprising frames secured to each side of the press plate, screw shafts carried by said frames, guide pin blocks slidably carried by said frames and operably associated with said screw shafts, guide pins carried by said guide pin blocks, a guide strap connecting the pins of one pin block with the pins of the other pin block, registers slidably arranged upon said guide strap and fingers carried by said registers.

3. A registering device for printing presses comprising frames secured to each side of the press plate, guide pin blocks slidably carried by said frames, manually

operable means for actuating said guide pin blocks, guide pins carried by said guide pin blocks, a guide strap connecting the pins of one pin block with the pins of the other pin block, registers slidably arranged upon said guide strap, fingers carried by said registers, an auxiliary guide strap secured to said guide strap and disposed in a plane at right angles to the plane of said guide strap and a telescoping register slidably carried by said auxiliary guide strap.

4. A registering device for printing presses comprising frames secured to each side of the press plate, guide pin blocks slidably carried by said frames, manually operable means for actuating said guide pin blocks, guide pins carried by said guide pin blocks, a guide strap connecting the pins of one pin block with the pins of the other pin block, registers slidably arranged upon said guide strap, fingers carried by said registers, an auxiliary guide strap secured to said strap and disposed in a plane at right angles to the plane of said guide strap, a tongue formed with rows of staggered graduations adjustably secured to said strap, and a casing adapted for telescoping relation with said tongue.

5. A registering device for printing presses comprising frames secured to each side of the press plate, guide pin blocks slidably carried by said frames, manually operable means for actuating said guide pin blocks, guide pins carried by said guide pin blocks, a guide strap connecting the guide pins of one pin block with the pins of the other pin block, registers slidably arranged upon said guide strap, fingers carried by said registers, an auxiliary guide strap secured to said guide strap and disposed in a plane at right angles to the plane of said guide strap, a tongue formed with rows of staggered graduations adjustably secured to said strap, a casing adapted for telescoping relation with said tongue and for movement in a plane at right angles to the plane of said auxiliary guide strap, alined ears carried by said casing and a finger arranged in said ears.

In testimony that I claim the foregoing as my own I have hereto affixed my signature in the presence of two subscribing witnesses.

ISADORE LEVIN.
